CENTRIFUGAL CLOTHES DRIER

Charles E. Morgenstern, St. Joseph, Mich., assignor to Nineteen Hundred Corporation, Binghamton, N. Y., a corporation of New York

Application December 27, 1937, Serial No. 181,843

3 Claims. (Cl. 210—72)

The invention relates to domestic laundry machines and particularly to centrifugal clothes dryers of the type generally referred to as spinners.

5 In the construction of centrifugal clothes dryers for domestic use it is usual to provide a cylindrical basket which is open at the top and has perforated sides. This basket is mounted for rotation within a cylindrical chamber, the driving means being located below this chamber and comprising a shaft extending up thru the bottom thereof and connected to the bottom of the basket. Within this arrangement, uneven distribution of the clothes in the basket results in 10 unbalanced centrifugal forces. These forces load the drive shaft and associated structure as a cantilever beam and cause vibration which is transmitted thru the driving means and its mounting to the frame of the machine. In order 15 to lessen vibration of the machine, the driving means for the spinner has been provided with a resilient mounting which permits a limited angular movement of the spinner in response to the unbalanced centrifugal forces, but constantly urges the basket into its normal upright position. When such a resilient mounting is employed, the unbalanced mass pulls the basket to one side as it begins to rotate so that its axis inclines from the normal vertical position. The 20 loaded basket thus wobbles or gyrates unsteadily about its mounting. As the speed of rotation increases the basket finally is restored to a position in which its axis remains almost stationary and the aforesaid unsteady gyration is reduced 25 to a practical minimum. In the process of reaching this stage of equilibrium, however, it will be apparent that the unsteady gyrations of the basket must result in rather severe vibration of the machine with consequent increase in bearing wear and a tendency to loosen the joints of the assembly. Furthermore the increased inertia of 30 the gyrating basket imposes a greater load on the motor with a resultant increase in power consumption.

45 It is an object of my invention to provide a spinner construction which will overcome to a large extent the aforementioned difficulties and which, in use, will more rapidly reach a state of equilibrium; that is to say, a construction in 50 which the time interval during which unsteady gyration continues is considerably shortened, so that, upon starting, the spinner will balance itself very rapidly.

55 Under certain conditions of operation it is possible that a spinner of the type heretofore-

known will not reach a condition of equilibrium at all, but will continue to gyrate with its axis away from the vertical even after it has reached its maximum speed. Thus, I have observed in connection with certain prior constructions that 5 with a small unbalanced load in the basket, such as produced when a single wet towel is placed therein at one side of the bottom, the basket will not pick up and find its true center. It is, therefore, a further object of my invention to provide a self-balancing basket which will overcome the unbalancing effect of eccentric loading under any and all normal conditions of operation.

A more specific object is to provide a self- 15 balancing centrifugal spinner which is adapted for use in conjunction with existing types of drying machines.

A further object is to provide a spinner construction which will produce only a minimum of 20 vibration, thus permitting the use of flexible or resilient mountings for the driving means. Other objects and advantages will appear as the description proceeds.

In the drawing I have shown a preferred embodiment of my invention, the view selected for illustration being an elevational view, partly in section, of a centrifugal drying basket and resilient supporting and driving means therefor.

In the usual domestic machine the drying unit 30 is associated with a washing unit, the two units being mounted on a single framework. Such a combination washer and drier is shown in my copending application Serial Number 86,522 filed June 22, 1936, and the centrifugal drier which 35 forms the subject of the present invention is adapted to be employed in such a combination if desired. The spinner consists of a perforated basket 1 which preferably is of cylindrical form having its side walls sloping inwardly at the top, 40 as at 2. The edge of the inwardly sloping wall portion 2 may conveniently terminate in an inwardly extending flange which as shown is provided with a curled edge 3 serving to prevent the water from splashing out at the top.

45 The bottom of the basket 1 is affixed to a shaft 4 carried by a gear case 5 which in turn is yieldably or flexibly secured to the framework of the machine. This yieldable connection should be located in line with the vertical axis of the 50 basket 1. For this purpose in the embodiment illustrated the gear case 5 is provided with a downward extension 6, preferably square in cross section. Surrounding the extension 6 is a bushing 7, of rubber or other resilient material. A 55

sleeve 8 is rigidly secured to a metal supporting strap 9 which in turn is secured directly to the frame of the machine. The sleeve 8 and strap 9 together provide a socket to receive the extension 6 of the gear case with its surrounding bushing 7. A shouldered disc 10, of rubber or other resilient material, backed by a metal disc 11, is secured to the lower end of extension 6 by means of a bolt 12 passing thru an aperture 10 in the supporting strap 9 so that the latter is clamped between the resilient bushing 7 and disc 10. In this manner the basket 1 is yieldably mounted on the fixed supporting strap 9 at a point in line with the axis of the basket. This 15 mounting, or such equivalent mounting as it may be desired to employ, permits the axis of the basket to incline thru an angle from the vertical, the angle of inclination being restricted however within narrow limits. This permits the 20 axis of the basket to gyrate about its normal vertical position while being constantly urged toward its normal position by the rubber bushing 7 and disc 10.

If desired, radial springs 13 secured at one 25 end to a flanged collar 14 affixed to the gear case 5, and at the other end to the frame of the machine, may be provided to assist in restoring the basket to its normal position. The disposition of these radial springs 13 may be 30 asymmetric as described in my copending application referred to hereinabove. The connection of the springs 13 to the frame may be adjustable; for example, the springs may be connected to pins 15 adjustably secured in brackets 16 35 attached to the frame.

The basket 1 is surrounded by a chamber which I have indicated diagrammatically by dot-dash lines 17, and suitable means are provided for sealing the opening thru which the drive 40 shaft extends, as for example the flanged tube 18, which is secured to the bottom of the chamber 16 and the upper end of which is connected to the shaft by means of a flexible bushing or sealing member 19. The driving means may 45 be of the construction disclosed in my copending application above referred to. A driving couple is indicated at 20 and this couple may form a part of a universal connection to the shaft of a motor (not shown). The drive to the 50 shaft 4 within the gear case 5 may comprise helical gears, and may also include a suitable clutch mechanism, these details not comprising a part of the present invention.

I have found that by increasing the mass of 55 the upper end of the basket 1 the spinner will quickly balance itself upon rotation, bringing the axis of the basket closely in line with its true vertical position. The increased mass so provided should be uniformly distributed around 60 the circumference of the basket as may be accomplished by the provision of a solid ring or collar 21 which is rigidly secured to the side walls of the basket by rivets 22 or other suitable attaching means. Instead of a continuous 65 ring it would be possible to use a series of independent weights uniformly distributed around the periphery of the basket in such a way that the added mass is symmetrically arranged with respect to the axis of the basket. The term 70 "uniformly distributed mass" as used in the specification and claims is intended to include such a series of independent weights as well as a continuous ring.

The tests which I have performed indicate 75 that with a basket 10½ inches in diameter, 14%

inches deep, and weighing 18 pounds, the use of a ring adding as little as 12 pounds to the mass of the upper end of the basket will overcome the effect of an off-balanced load in the form of wet clothing or other articles carried 5 by the basket. I have found it desirable that the mass at the periphery of the upper portion of the basket be substantially greater than the mass of the basket adjacent to the bottom in order to achieve an adequate self-balancing effect. With this construction the gyroscopic 10 effect achieved brings the axis of the basket quickly to a fixed position. At the beginning of rotation of the basket the upper end of its axis describes an orbit which is a function of 15 the unbalancing effect of the load and the restraining action of the resilient mounting. As the speed of rotation increases the gyroscopic effect of the weighted upper end of the basket quickly reduces the size of this orbit until the 20 axis reaches its true vertical position. At this point the novel spinner construction which I have described eliminates substantially entirely the effect of the unbalanced centrifugal forces imposed by the loaded basket, causing it to 25 rotate with little if any vibration.

The position and mass of the ring 21 may be varied somewhat to suit varying conditions, this depending in part on the magnitude of the resilient restoring forces applied by the rubber mounting or by the springs, or by both. It may also depend to a certain extent on the total mass of the basket 1. It would seem perhaps that the location of an additional mass at a 30 distance from the point of support would increase the difficulty of bringing the basket into equilibrium because this mass is initially thrown out of line by the unbalanced load and exerts a centrifugal force normal to the axis of the spinner which must resist this force as a cantilever beam. I have found, however, that such an effect is more than compensated for by the 35 inertia forces generated in the rotating mass when located in the manner I have described. The mass may be placed somewhat lower down 40 on the upper part of the basket, or it may be distributed over a greater portion of the length of the basket, but the center of the added mass should remain appreciably above the center of 45 the basket. I prefer to bring the center of mass 50 of the added weight as close as possible to the upper end of the basket.

If desired, the resilient mounting of the gear case 5 may be replaced by a simple ball and socket connection or other flexible connection 55 permitting a limited inclination of the axis of the basket. Alternatively, the rubber mounting may be retained but the springs 13 omitted.

Other modifications in the construction as 60 specifically described may be made without departing from my invention and I have no intention of excluding any such modifications or equivalents of the invention as claimed.

I claim:

1. A centrifugal drier comprising a basket, a 65 fixed support positioned below said basket, the lower part of said basket being connected to said fixed support by a resilient mounting, said mounting being arranged to provide for rotation of said basket about a substantially vertical axis, and a balancing mass rigidly associated with the upper part of said basket.

2. A centrifugal drier comprising a basket arranged for rotation about a vertical axis, means 70 for rotating said basket, a flexible mounting for 75

said basket arranged at the axis of rotation and below the basket, and a uniformly distributed mass concentrated at the upper part of said basket.

5. 3. A centrifugal drier comprising a basket having cylindrical side walls, said basket being arranged for rotation about its axis, means for rotating said basket, a flexible mounting for said

basket arranged at the axis of rotation and below the basket, resilient means for urging said basket into a position in which its axis is substantially vertical, and a circular ring of substantial mass secured directly to said cylindrical 5 walls at the upper part of said basket.

CHARLES E. MORGENSTERN.
